RUNABOUT VEHICLE BODY

Richard T. Priestley, Los Angeles, Calif., assignor to
Motion Industries, Inc., Culver City, Calif.

Filed Aug. 17, 1972, Ser. No. 281,304

Term of patent 14 years

Int. Cl. D12—14

U.S. Cl. D14—3 R

FIG. 1

FIG. 2

FIG. 3

FIG. 4

FIG. 5

FIG. 6

FIG. 1 is a perspective view of the runabout vehicle body showing my new design;

FIG. 2 is a top plan view thereof;

FIG. 3 is a side elevational view thereof;

FIG. 4 is a bottom plan view thereof;

FIG. 5 is a rear elevational view thereof; and

FIG. 6 is a front elevational view thereof.

The broken lines shown in the drawing are for illustrative purposes only.

I claim:

The ornamental design for a runabout vehicle body, as shown and described.
